(57) **CLAIM**

The ornamental design for a charger, as shown and described.

DESCRIPTION

FIG. 1 is a front, top perspective view of a charger showing our new design;

FIG. 2 is a side elevational view thereof, the other side being a mirror image thereof;

FIG. 3 is a top plan view thereof;

FIG. 4 is a front elevational view thereof;

FIG. 5 is a rear elevational view thereof;

FIG. 6 is a bottom plan view thereof;

FIG. 7 is a front, top perspective view of a charger showing a second embodiment of our new design;

FIG. 8 is a side elevational view thereof; the other side being a mirror image thereof;

FIG. 9 is a top plan view thereof;

FIG. 10 is a front elevational view thereof;

FIG. 11 is a rear view thereof; and,

FIG. 12 is a bottom plan view thereof.

The broken line showing of a power cord on the bottom of the charger is for illustrative purposes and forms no part of the claimed design.
